UNITED STATES PATENT OFFICE

156,224

DESIGN FOR A SORTING MACHINE

Eugene A. Ford, Endicott, N. Y., assignor to International Business Machines Corporation, New York, N. Y., a corporation of New York

Application May 3, 1947, Serial No. 138,807

Term of patent 14 years

(Cl. D55—1)

To all whom it may concern:

Be it known that I, Eugene A. Ford, a citizen of the United States of America and resident of Endicott, Broome County, in the State of New York, have invented a new, original, and ornamental Design for a Sorting Machine, of which the following is a specification, reference being had to the accompanying drawing, forming part thereof.

Fig. 1 is a perspective view showing the top, one side and one end of a sorting machine embodying my new design; and

Fig. 2 is a perspective view showing the top, other side and other end thereof.

I claim:

The ornamental design for a sorting machine, substantially as shown and described.

EUGENE A. FORD.
